CLAIM

I claim the ornamental design for a display stand, as shown and described.

DESCRIPTION

FIG. 1 is a perspective view for a display stand;
 FIG. 2 is a side elevational view thereof;
 FIG. 3 is a side elevational view, opposite the FIG. 2 side view, thereof;
 FIG. 4 is a front elevational view thereof;
 FIG. 5 is a rear elevational view thereof;
 FIG. 6 is a top plan view thereof; and,
 FIG. 7 is a bottom plan view thereof.

PATENT NO. : D637,016 S
APPLICATION NO. : 29/365558
DATED : May 3, 2011
INVENTOR(S) : Axel Pohl

Page 1 of 1

It is certified that error appears in the above-identified patent and that said Letters Patent is hereby corrected as shown below:

Title page, item (56) References Cited – Replace “467,621 A 1/1892 Mets”
with --467,821 A 1/1892 Mets--

Title page, item (57) Claim – Replace “stand, an as shown” with --stand as shown--

Signed and Sealed this
Twelfth Day of February, 2013

Teresa Stanek Rea
Acting Director of the United States Patent and Trademark Office
